Primary Examiner — Cynthia Underwood(74) Attorney, Agent, or Firm — Griffiths & Seaton PLLC; JoAnn M. SeatonCLAIM

The ornamental design for a plate, as shown and described.

DESCRIPTION

FIG. 1 is a front, perspective view of a plate showing our new design;

FIG. 2 is a front view thereof, the rear view being identical to the front view;

FIG. 3 is a right side view thereof, the left side view being identical to the right side view;

FIG. 4 is a top view thereof; and,

FIG. 5 is a bottom view thereof.

The broken lines represent portions of the plate that form no part of the claim. The dash-short dash boundary lines indicate the bounds of the claimed design and form no part of the claimed design.

1 Claim, 4 Drawing Sheets(56)
